(57) **CLAIM**

The ornamental design for a transcranial stimulation device, as shown and described.

DESCRIPTION

FIG. 1 is a front view of a transcranial stimulation device; FIG. 2 is a back view of the transcranial stimulation device; FIG. 3 is a first side view of the transcranial stimulation device;

FIG. 4 is a second side view of the transcranial stimulation device; and,

FIG. 5 is a top plan view of the transcranial stimulation device.

The broken line shown in the drawings is included for the purpose of illustrating portions of a transcranial stimulation device and forms no part of the claimed design.
